ORNAMENTAL ILLUMINATING DEVICE

Filed Sept. 26, 1928

Fig. 1,

Fig. 2,

UNITED STATES PATENT OFFICE

ALBERT SADACCA, OF NEW YORK, N. Y., ASSIGNOR TO NOMA ELECTRIC CORPORATION,
OF NEW YORK, N. Y., A CORPORATION OF NEW YORK

ORNAMENTAL ILLUMINATING DEVICE

Application filed September 26, 1928. Serial No. 308,497.

This invention relates to ornamental illuminating devices. More particularly it relates to an electric Christmas candle simulating unit.

5 An object of this invention is to provide a device of the character described which may be connected directly to a source of electric power, or in parallel circuit to other similar units to produce a plurality of "Christmas 10 candles" of equal brightness which may be placed in various parts of a room and yet be fed by a single source of power.

15 A further object of this invention is to provide a highly ornamental device of the character described which shall be rugged in construction, easy to connect either to a source of power or to other similar devices, and which shall yet be simple and inexpensive to manufacture and practical and efficient to a 20 high degree in use.

Other objects of this invention will in part be obvious and in part hereinafter pointed out.

The invention accordingly consists in the 25 features of construction, combinations of elements, and arrangement of parts which will be exemplified in the construction herein-after described, and of which the scope of application will be indicated in the following 30 claims.

In the accompanying drawing, in which is shown one of the various possible illustrative embodiments of this invention,

Fig. 1 is a perspective view of two units 35 with parts broken away embodying the invention showing the electrical fitting detached;

Fig. 2 is a cross-sectional partial view of the device; and

40 Fig. 3 is a perspective view of the base and a portion of the "candle" with the wiring removed.

Referring in detail to the drawing, 10 designates a device made in accordance with 45 the invention, which is here seen to comprise an ornamental base 11 made of wood or any other suitable material having an opening 12 in the top surface 13 thereof. Said opening 12 constitutes a chamber 12a having a bottom wall 12b. Said chamber 12a communi-

cates with aligned cross passages 14, 14a opening on opposite sides 15, 16 respectively of said base. An elongated tubular member 17 made of papier mâché or other suitable material and decorated as at 17a to simulate a candle, is inserted in said opening 12, the lower end 17b of said member abutting the bottom wall 12b of said chamber 12a. Said tubular member 17 is preferably provided at its lower extremity 17b with diametric cut out portions 18, 19 registering with said passages 14, 14a respectively. 55

The upper end portion 20 of said tubular member 17 is provided with a short tubular member 21 snugly fitting the inner surface 22 of said end portion 20. Mounted within said member 21 is screw threaded lamp socket 23 receiving in the upper open end thereof, the screw threaded base 24 of an ornamental lamp 25. Said lamp 25 may be 60 tapered and colored to simulate a candle flame. 65

Extending within said tubular member 17 are wires or leads 30, 31 the upper end thereof being soldered to the central contact 32 and shell 33 respectively of socket 23. The lower ends 30a, 31a of said wires 30, 31 are soldered to conductors 34, 35 respectively extending thru passages 14, 14a, cut out portions 18, 19 and chamber 12a. Said conductors 34, 35 constitute a duplex cable 36, a portion of the insulation 37 thereof being removed as at 38 to permit the soldered connections 30a, 31a. These connections may be insulated from one another by tape 39 suitably applied in a manner well known in the art. It will be noted that chamber 12a provides the space necessary for said soldered joints 30a, 31a. 75

80 One end 36a of said cable 36 extends beyond said base 11 and is preferably connected to an ordinary blade plug attachment member 40 for connecting to a source of electric power. An ordinary screw plug fitting 41 may be provided with openings 42 for receiving the blades of member 40, and may thereby be attached to said member 41 to constitute a single attachment fitting for attaching said device 10 to a screw socket (not shown) for receiving power. The opposite 85 90 95 100

end 36b of said cable 36 also extends from said base 11 and may be connected to an ordinary blade plug receiving socket 43. Said socket 43 is preferably adapted for attachment to a plug similar to plug 40, for a purpose hereinafter appearing.

The numeral 50 designates a device (the lower portion thereof only, being shown in Fig. 1) similar to device 10. This outfit 10 is shown with the screw plug attachment 41 removed, the blade plug 51, similar to plug 40, being receivable in socket 43 for connecting said device 50 in parallel circuit to device 10. Said device 50 is also provided with a socket 52 similar to socket 43. It is thus apparent that a number of said units 10, 50 may be connected to a single power source to produce a series of electric "Christmas candles" in parallel relation. All of the 20 lamps 25 in such a series of candles will have similar voltages and will consequently be of equal brightness when illuminated. Said units may be placed in different parts of a room, being movable relatively to one another and connected by the flexible cable 36.

It will thus be seen that there is provided a device in which the several objects of this invention are achieved, and which is well adapted to meet the conditions of practical use.

As various possible embodiments might be made of the above invention, and as various changes might be made in embodiment set forth, it is to be understood that all matter herein set forth or shown in the accompanying drawing is to be interpreted as illustrative and not in a limiting sense.

Having thus described my invention, I claim as new and desire to secure by Letters Patent:

1. In a device of the character described, a base having an opening in the top surface thereof, a pair of passages extending thru said base on opposite sides thereof and communicating with said opening, a socket supporting tubular member mounted on said base and having a portion received in said opening, a socket mounted in said supporting member, conductors within said passages extending from said base, leads within said tubular member connecting said conductors to said socket, a plug device connected to said conductors extending through one of said passages, and a socket device connected to said conductors extending thru another of said passages.

2. In a device of the character described, a base having an opening in the top surface thereof forming a chamber having a bottom wall, aligned passages within said base communicating with said chamber, a tubular member inserted within said opening, the lower end of said member abutting said bottom wall and provided with cut out portions registering with said passages, a lamp socket

mounted in said tubular member at the upper end thereof, conductors extending thru said chamber and passages, and leads within said tubular member connecting said socket to said conductors.

3. In a device of the character described, a base having an opening in the top surface thereof forming a chamber having a bottom wall, aligned passages within said base communicating with said chamber, a tubular member inserted within said opening, the lower end of said member abutting said bottom wall and provided with cut out portions registering with said passages, a lamp socket mounted in said tubular member at the upper end thereof, conductors extending thru said chamber and passages, and leads within said tubular member connecting said socket to said conductors, said conductors being connected to a plug member and a socket member at the opposite ends thereof.

In testimony whereof I affix my signature.

ALBERT SADACCA.
